UNITED STATES PATENT OFFICE.

RAYMOND W. KEELER, OF GALION, OHIO, ASSIGNOR TO THE GALION IRON WORKS & MFG. CO., OF GALION, OHIO, A CORPORATION OF OHIO.

SCARIFIER FOR TRACTORS.

Application filed July 8, 1924. Serial No. 724,906.

To all whom it may concern:

Be it known that I, RAYMOND W. KEELER, a citizen of the United States, residing at Galion, in the county of Crawford and 5 State of Ohio, have invented certain new and useful Improvements in Scarifiers for Tractors, of which the following is a specification.

This invention relates to road working 10 machines, and particularly to motor operated road working machines using the motor mechanism of the Fordson tractor mounted upon a special frame, as illustrated, described and claimed in my pending 15 application for patent Serial #724,907 filed on the 8th day of July 1924.

This invention particularly relates to road scarifying machines peculiarly designed for mounting upon the tractor frame 20 illustrated in my pending application above referred to, the scarifier embodying in a general way a tooth-carrying bar mounted upon the rear end of the machine for vertical movement.

25 An object of the invention is to provide a scarifier of this character with manually operable means whereby the tooth-carrying bar may be depressed to bring the teeth into engagement with the road, and to provide means which will resiliently urge the tooth-carrying bar downward so as to permit the tooth-carrying bar to rise when the teeth come in contact with an obstruction as, for instance, stones or other material 30 which would tend to break the tooth-carrying bar but which will immediately act to depress the tooth-carrying bar into engagement with the earth and give it an elastic pressure against the road.

40 A still further object is to provide means for keeping the teeth mounted upon said bar always at the same angle of engagement with the ground, whether the teeth be depressed much or little.

45 A still further object is to provide an improved form of tooth-carrying bar of very simple and effective construction so constructed that two sets of teeth may be mounted upon the bar and the teeth be individually adjustable so as to bring the points in contact with the road and to compensate for any wear of the teeth and per-

mit, of course, the removal of any broken tooth and the re-insertion of a fresh tooth whenever required.

55 My invention is illustrated in the accompanying drawings, wherein:—

Figure 1 is a rear elevation of a tractor having a scarifying attachment constructed in accordance with my invention applied thereto;

Figure 2 is a fragmentary sectional view 60 of the rear end of the tractor showing the scarifying mechanism in elevation;

Figure 3 is a sectional view through the 65 tooth-carrying bar and one of the plunger housings, the section being taken in a vertical plane longitudinally of the machine;

Figure 4 is a perspective view of the 70 scarifying bar.

In the drawings, I have illustrated so much of a tractor as is necessary for an understanding of my invention, and in these drawings 10 designates the rear ends of the supporting beams of the tractor. These 75 beams are spaced apart at their rear ends and, as indicated, are of channel iron. The rear axle of the machine is mounted in bearings upon these rearwardly extending ends.

The transverse channel beam 11 is connected 80 to the beams 10, and mounted upon the middle of this transverse channel beam 11 is a screw shaft supporting bracket, designated generally 12, the lower end of which is formed to provide an angular flange 13 85 which is riveted, bolted or otherwise connected to the beam 11. The bracket 12 is formed to provide upper and lower bearings 14 and 15 for the worm 16 which is mounted upon the worm shaft 17 and supported in said bearings. Mounted in the

brackets 18, which in turn are mounted upon the upper flanges of the beams 10 at the rear ends thereof, is a shaft 19 which carries upon it at the middle of the machine the 95 worm sector 20, this sector having teeth engaged by the worm 16. The worm segment has a radially extending arm 21 formed with a transversely elongated barrel 21^a at its outer end. On opposite ends of the beam 100 11 are mounted the brackets 22, these brackets each being provided with a pair of bearings 23 and 24 in a vertical relation.

Rearward of the beams 10 is disposed the

scarifier beam 25 which, as illustrated, is I-shaped in cross section, the upper and lower webs 26 and 27 respectively of the beam being disposed in a horizontal position, while the vertical web of the beam is disposed at a downward and forward inclination. These upper and lower webs 26 and 27 are notched at intervals for the reception of the scarifier teeth 28. These scarifier teeth are square in cross section and pyramidal at opposite ends. The notches 29 in the forward edges of the upper and lower webs are disposed in staggered relation to the notches 29 in the rear edges of the upper and lower webs and the teeth are disposed in said notches and held in place by means of U-bolts 30 which pass through the vertical web 25 of the toothed bar.

Formed integral with the toothed bar 20 and inward from each end are a pair of ears 31, and inward of this pair of ears 31 there is pivoted to the bar a forwardly extending link 32. The link 32 is pivoted to the bar at 33. The outer end of the link 32 is perforated for the passage of a pivot pin 34 which passes through the lowermost ears 24. Pivoted to the uppermost ears 23 are the rearwardly extending links 35, which in turn are pivoted by a pivot pin 36 to the ears 31. There are two of these links 35 and two of the links 32, and it will be seen that the toothed bar is mounted for swinging movement in a vertical plane about the axis of the pivot pin 34 and that inasmuch as there are two of these links 32 and 35 each connected to the tooth-carrying bar, the tooth-carrying bar will be sufficiently shifted as the links 32 and 35 move downward to compensate for the change in the angle of the links 32 and 35 and keep the upper and lower webs 26 and 27 of the tooth-carrying bar always in a horizontal position.

For the purpose of vertically oscillating the tooth-carrying bar, I mount upon the pivot rod 33 or pivot pin or otherwise pivotally connect to the tooth-carrying bar 26 the plungers 37. Each plunger is cylindrical in form, one end of the plunger being formed with an eye for the reception of the pivot pin 33, the opposite end of the plungers being rounded off and the middle of the plunger being formed with an outstanding annular collar or shoulder 38. Pivoted upon the extremity of the arm 21 is a cylindrical housing 39 which is hollow and which at its upper end is formed with an ear 40, through which the pivot pin 41 passes, which connects the plunger to the barrel 21. The lower end of the housing is closed by an annular cap plate 42 which may be attached to the flanged lower end of the housing in any suitable manner. Disposed within the housing and exerting pressure upon the shoulder 38 is the spring

43 which bears at its upper end against the upper wall of the interior of the housing and at its lower end bears against this shoulder and as a consequence urges the plunger downward until the shoulder 70 strikes the cap plate 42 which acts as a limiting stop.

It will be obvious now that when the scarifying bar is depressed by depressing the arm 21, that is by lifting the segment 75 20, that the depression of this arm 21 will cause the downward movement of each housing and thus, through the action of the spring on the shoulder, will cause the downward movement of each plunger 37 80 and the downward movement of the scarifier bar, but that if the scarifying teeth should strike some obstruction as, for instance, a stone or any other impediment which might act to break the teeth, the strain will cause the upward movement of the plunger against the action of the spring 43. Therefore, the spring 43 acts to yieldingly hold the teeth to their work.

Also mounted upon the pins 33 which pivotally engage the end of the plunger rod with the toothed bar are the wheels 44. These wheels are two in number and disposed at opposite ends of the bar and normally run upon the ground and limit the downward movement of the scarifier. The purpose of this scarifier is to force the teeth down into the road bed to a certain degree and the machine moves along, causing the teeth to cut up the road bed and 100 scarify it. The teeth are placed at such an inclination that they perform this action without placing undue strain upon the teeth themselves.

Preferably the shaft 17 carries at its upper end a hand wheel 45 whereby the shaft 17 may be operated and whereby the worm wheel 20 may be operated.

The operation of the device is obvious from what has gone before. It will be seen that this device is very compact, simple, positive in its action and strong, and that the teeth are always presented to the road bed at the same angle.

It will likewise be seen that the two housings with the interior springs permit one end of the scarifying bar or tooth-carrying bar to be raised while the other end is held depressed to its full extent by the spring so that thus the tooth-carrying bar may ride over obstacles which are present beneath one end of the bar and which are not present at the other end of the bar, and furthermore such a construction will permit the tooth-carrying bar to take an angular relation to a horizontal plane as, for instance, in working on roads which are laterally inclined or crowned. This I regard as a very important feature of the invention.

The tractor mechanism which I have dis-

closed in my pending application before referred to is designed to support a planer such as is disclosed in my pending application Serial #724,907 filed on the 8th day of July, 1924, and also this scarifying attachment so that the complete tractor will provide a road roller, a planer and a scarifier. The scarifier will preferably be used when the planer is not used and vice versa, but the attachment is designed to make the roller tractor which I have disclosed in the application before referred to a complete road working machine.

I claim:—

1. The combination with a tractor, of a scarifying mechanism connected therewith comprising a tooth carrying bar, links pivotally connecting the bar to the rear end of the tractor and permitting upward and downward movement of the scarifying bar, means for raising or lowering the scarifying bar comprising a segment gear having a radially extending arm, the arm at its extremity being laterally extended in opposite directions to form a transversely extending barrel, manually operable means engaging the segment gear whereby the segment gear may be oscillated, a pair of members pivoted to the axis of said elongated barrel and depending therefrom, a pair of members having telescopic engagement with the first named members and pivotally connected to the tooth carrying bar, means limiting the outward movement of one telescopic member with relation to its coacting other telescopic member, and a spring yieldingly resisting the inward

movement of the members one into the other.

2. The combination with a tractor, of scarifying means coacting therewith comprising a tooth carrying bar, a plurality of pairs of links pivotally connected to the bar and to the tractor, the pairs of links being disposed in a plurality of vertical planes, means for raising or lowering the tooth carrying bar including an oscillatory member pivotally mounted for oscillation in a vertical plane and having an outwardly extending arm formed at its end with a transversely extending barrel, a pair of coacting telescopic members connected to each end of the barrel and to the tooth carrying bar, and springs resisting the movement of one of said members into the other member of the same pair, said spring yieldingly urging the scarifying bar downward but permitting the independent upward movement of opposite ends of the scarifying bar.

3. In a scarifier of the character described, a scarifying bar I-shaped in cross section to provide upper and lower flanges and a connecting web, the upper and lower flanges having aligning notches, the notches on the edge faces of the flanges on one side of the bar being in staggered relation to the notches in the edge faces of the opposite side of the bar, teeth engaged in said notches, and U-bolts engaging said teeth and passing through the web of the bar.

In testimony whereof I affix my signature.

RAYMOND W. KEELER.
